UNITED STATES PATENT OFFICE

WILLIAM J. DODD, OF MIAMI, OKLAHOMA

PRICE CARD HOLDER

Application filed March 19, 1931. Serial No. 523,865.

My invention relates to improvements in price card holders, and it consists in the combinations, constructions and arrangements herein described and claimed.

An object of my invention is to provide a price card holder of very simple construction, which can be manufactured cheaply and sold at a relatively low price.

A further object of the invention is to provide a device of the type described which will firmly grip a box, board, sheet or other support, but which dispenses with the use of springs.

A further object is to provide a device in which the gripping member also serves as a card holding member, thus simplifying the device.

A further object is to provide a price card holder which may be instantly applied or instantly released and in which the action of the gripping member is largely effected through gravity, as distinguished from spring actuated gripping members.

Other objects and advantages will appear in the following specification, and the novel features of the invention will be particularly pointed out in the appended claims.

My invention is illustrated in the accompanying drawings forming part of this specification, and in which:

Figure 1 is a perspective view of my improved card holder as applied to the edge of a container.

Figure 2 is a longitudinal section through the device as applied to a container.

Figure 3 is a sectional view along the line 3—3 of Fig. 2, and,

Figure 4 is a sectional view showing the device as applied to a container having thinner walls.

In carrying out my invention I make use of two pieces of sheet metal. One of these pieces has a central portion comprising a body 1 having a portion 2 bent angularly with respect thereto, and a flange 3 bent substantially at right angles to the portion 2, as shown in the drawings. The portion 1 has ears 4 and 5 which are bent to the rear of the portion 1 to form with the portion 1 an

elongated loop. In Figure 3 I have shown the ears 4 and 5 as being bent so as to have their adjacent portions lying in a common plane substantially parallel to the surface of the body portion 1.

Integral with the body portion is an extension 6, which, as will be seen, is bent forwardly at 6a and then upwardly at 6b. The ends of this integral portion are curved rearwardly, as shown at 6d and 6e.

The companion member consists of a plate or bar 7 bent at its upper end to form a bead 7a. At a point 7b near its lower end is bent angularly to form a gripping portion 7c, which is substantially parallel with the flange 3 in any position of the gripping portion.

From the foregoing description of the parts of the device the operation thereof may be readily understood.

When it is desired to secure the price card holder to a container, such as the box 8 shown in dotted lines in Fig. 1, the flange 3 is placed over the edge of the box, so that the portion 2 is brought into contact with the edge, and the member 7 is permitted to drop until the gripping portion 7c engages the opposite face of the wall of the container or box. A price card 9 is then placed between the member 6 and the member 7. In order to do this it is necessary to bend the card slightly so that the card is in frictional contact with the curved portions 6d and 6e of the member 6 on one side and with the face of the member 7 on the other, see Fig. 3. This holds the card securely by frictional contact.

The price card holder is automatically adjustable for containers having walls of different thickness, or for cards, sheets or other supports of varying thickness.

In Fig. 4 I have shown a container having a thin wall 10. The upper edge of this wall forms a support for the portion 2 and the member 7 slides down until the gripping portion 7c is in contact with the face of the wall on one side, the flange 3 being in contact with the face on the opposite side. The holder is thus held securely, regardless of the thickness of the wall upon which it is secured. It

may be instantly taken off, and as quickly applied, thus dispensing with springs while providing a positive gripping action.

As will be seen from Figure 3, the curved ends 6d and 6e of the extension 6 extend rearwardly of the front face of the slidable member 7, so that the card 9 when inserted between the extension and the gripping member is bent and held frictionally by the curved ends of the extension on one side, and by the face of the gripping member on the other. One purpose in curving the ends of the extension is to prevent any sharp edges from catching or digging into the card, thus facilitating the insertion and withdrawal of the card.

I claim:—

1. A price card holder comprising a body portion having rearwardly turned ears and being provided with a portion bent at an obtuse angle, a flange carried by said angularly bent portion for engaging one face of a support, a gripping member slidably disposed between the rearwardly turned ears, the plane of the gripping member being angularly disposed with respect to the plane of the flange, and a gripping portion carried by said slidable gripping member for engaging the opposite face of the support, said gripping portion being parallel to the flange in any position of the slidable member.
2. A price card holder comprising a body portion having rearwardly bent ears and being provided with an angularly bent portion, a flange integral with said angularly bent portion, a gripping member slidably disposed between the ears, the plane of the gripping member being angularly disposed with respect to the plane of the flange, a gripping portion carried by said slidable member, said gripping portion being parallel with the flange, an extension carried by the body portion and being offset from the plane thereof, said extension having rearwardly curved end portions, and being spaced from the gripping member, the space between the extension and the gripping member serving as a receptacle for a price card.
3. In a price card holder, a body portion, a slidable gripping member carried by said body portion on the rear thereof, an extension to said body portion offset from the plane thereof, and being provided with curved end portions, said extensions being spaced from said gripping member and the end portions extending rearwardly of the front face of the gripping member, whereby a card inserted between the extension and the gripping member is held frictionally.
4. A price card holder comprising a body portion and being provided with a portion bent at an obtuse angle, a flange integral with said angular bent portion, a gripping member slidably carried by the body portion, the plane of the gripping member being

angularly disposed with respect to the plane of the flange, and a gripping portion carried by said slidable member said gripping portion being parallel with the flange in any position of the slidable member.
